TEST TUBE RACK

Jose F. Sendra and Joaquim Fernandes, Miami, Fla.,
assignors to American Hospital Supply Corporation,
Evanston, Ill.

Filed Mar. 21, 1973, Ser. No. 343,542

Term of patent 14 years

Int. Cl. D24—02; D6—99
U.S. Cl. D16—1 A

FIG. 1

FIG. 2

FIG.3

FIG.4

FIG.5

FIG. 6

FIG. 1 is a perspective view of a test tube rack embodying our new design;

FIG. 2 is a top plan view of the rack;

FIG. 3 is a front elevational view;

FIG. 4 is a bottom view;

FIG. 5 is a rear elevational view; and

FIG. 6 is an elevational view of one end, the opposite end being the same but in reverse.

We claim:

Design for a test tube rack, substantially as shown and described.
